UNITED STATES PATENT OFFICE,

WILLIAM BERGNER, OF BALTIMORE, MARYLAND, ASSIGNOR TO FREDERICK BERGNER & CO., OF SAME PLACE.

DESIGN FOR AN ALBUM-CASE.

SPECIFICATION forming part of Design No. 20,347, dated November 25, 1890.

Application filed October 6, 1890. Serial No. 367,276. Term of patent 3½ years.

To all whom it may concern:

Be it known that I, WILLIAM BERGNER, a citizen of the United States, residing at Baltimore, in the State of Maryland, have invented and produced a new and original Design for Album-Cases, of which the following is a specification.

In the accompanying drawings, forming part of this specification, Figure 1 is a perspective view of my design for album-cases. Fig. 2 is a view of the ornamental frame separate from the case. Fig. 3 is a sectional view of the ornamental frame.

This is an album-case having on its exterior an ornamental frame with an open cen-

ter. The album-case A is rectangular in shape and sets on a base-board b in an upright or nearly vertical position. On the exterior side of the album-case is the open-center frame C, having a fanciful face and an indented border.

I claim—

The design for album-cases, substantially as herein shown and described.

In testimony whereof I affix my signature in the presence of two witnesses.

WILLIAM BERGNER.
